G. W. WALSH

OIL BURNER

Filed Jan. 9, 1922

Witness:
R. J. Hamilton 34

UNITED STATES PATENT OFFICE.

GEORGE W. WALSH, OF KANSAS CITY, KANSAS.

OIL BURNER.

Application filed January 9, 1922. Serial No. 527,997.

To all whom it may concern:

Be it known that I, GEORGE W. WALSH, a citizen of the United States, and resident of Kansas City, county of Wyandotte, State of Kansas, have invented a certain new and useful Improvement in Oil Burners, of which the following is a complete specification.

This invention relates to oil or distillate burners and has for one of its objects to produce a burner of this character in which the oil feed lines and generator are protected against the deposit thereon of carbon.

Another object is to produce a burner in which the generator is so constructed that vaporized fuel entering therein shall be widely and uniformly distributed and held under sufficient pressure to insure a steady flame at the point of combustion.

A further object is to produce a burner of the character set forth in which the gas generated is super-heated before it issues through the jet orifice and is thus in the best possible condition for ignition.

A still further object is to produce a burner of the character set forth of simple, strong, durable, efficient and inexpensive construction; and in order that it may be fully understood, reference is to be had to the accompanying drawing, in which:—

Figure 1 is a top plan view of the burner.

Figure 2 is a section on the line II—II of Figure 1.

Figure 3 is an enlarged central vertical section taken through a part of the device.

Figure 4 is an enlarged central vertical section taken through the jet of the burner.

In the said drawing, where like reference characters identify corresponding parts in all of the figures, 2 illustrates a gas generator of substantially hollow discus form. The inner face of the upper part of the generator is formed with a series of concentric flutes 3, which will tend to direct fuel entering the generator downwardly toward the bottom of the same, as will be described hereinbelow.

At diametrically opposite points, the generator is provided with a pair of enlargements 4 which are internally threaded for the reception of nipples 6, respectively engaged with elbows 8. The elbows 8 are connected to stand pipes 10 by means of pipe connections 12 and nipples 14, the lower ends of said stand pipes being connected by means of elbows 16 and pipe sections 18,

one of said pipe sections being joined by means of a union 20 for convenience in assembling the burner, to a T-coupling 22. The other leg of said coupling is in communication with a pipe 24 leading to any suitable source of liquid fuel supply.

As well known to those skilled in the art, when the burning gas is allowed to directly contact with a generator or pipe in which liquid fuel is contained, a film of carbon will be formed on the exterior face of such container. In order to overcome this objectionable deposit of carbon, the bottom of the generator 2 will be protected by means of a shield 26, of slightly concave form to conform to the shape of the generator, and said generator will preferably contact with the shield only at its bottom and at the bottoms of its two enlargements 4, as illustrated, the shield being bifurcated at diametrically opposite points 28 in order to receive the nipples 14 and be supported by the pipe connections 12, as illustrated.

Communicating centrally of the top of the generator, is a pipe 30 which is connected to a vertical pipe 31 leading downwardly through a passageway 32 formed in the generator and connected at its lower end to a pipe 34 which is formed into a coil 36, dependently supported by said pipe 31 centrally of the bottom of the shield 26. The lower end of the coil is connected to a short pipe section 38, closed at its end by a cap 40, and centrally of the coil, provided with a threaded opening for the reception of a jet tip 42 provided with an orifice 44 for the discharge of gas, as will be hereinafter described.

Each of the stand pipes 10 is protected from deposits of carbon by means of sleeves 46 of slightly greater diameter than the pipes in order to provide an air space around the same. The coil 36 is provided with an internal casing 48, flanged at its upper end as at 50 for engagement with the upper convolution of the coil and depending therefrom. This shield is provided in order to protect the coil from direct contact with the flame for the purpose of protecting the same and also in order that the flame may be directed vertically upward and projected directly against the under face of the shield.

The operation of the burner is substantially, as follows: Oil is permitted to flow into the generator until same is filled, and

then the flow of such oil is cut off. A small quantity of fuel is now poured on the upper part of the generator and will follow the surface thereof and will be deposited in the 5 concave shield 26. This liquid fuel is now ignited and the heat of such burning oil will commence the generation of gas within the generator. As soon as the operator notices gas escaping from the jet orifice 44, 10 he will ignite such gas and the flame thereof will be directed upwardly through the casing 48 and will contact with the bottom of the shield 26 and will then be projected outwardly between the curved portion 50 of 15 the casing and the bottom of the shield. The operator will now open the fuel supply valve (not shown) in order that the supply of fuel to the burner shall be continuous.

The gas passing through the coil will be 20 superheated by the flame within the casing 48. In this connection it is desirable to state that when the coil is not employed, the flame will have a more or less yellow color showing the presence of red hot, but unconsumed, 25 carbon particles, but that when the coil is in position the flame will be white.

The deposit of carbon on the bottom of the shield 26 and on the sleeves 46 is avoided 30 by the fact that all of said members are provided with an air space on their opposite sides, thus permitting the said parts to be heated to substantially the same temperature on both of their faces.

After the burner has been in operation for 35 some time, sufficient gas is generated to cause the backing up of the liquid fuel to some point in the stand pipes, and the generator stands substantially completely charged with 40 gas. It will be understood, however, that more or less liquid fuel will at times be drawn into the generator. When the entry of this liquid fuel occurs it will strike the concentric fluted surface 3 of the under face 45 of the upper part of the generator and will thus be deflected downwardly to the bottom of the generator where it will be immediately evaporated by contact with the hot surface thereof. By placing the fuel pipes at diametrically opposite points it is also believed that the flutes will set up a whirling 50 action in the gas when the latter enters the generator.

The passageway 32 is provided in order 55 that the pipe 32 may be protected from direct contact with the flame, it being apparent from the drawing that the only exposed portion will be that part of pipe 31 passing between the plane parallel with the bottom of the shield and the plane of the top of the 60 curved portion of the casing.

From the above description, it will be apparent that I have produced a burner of the character described which possesses all of

the features of advantage set forth as desirable, and while I have described and 65 claimed the preferred embodiment of the same, I reserve the right to make all changes properly falling within the spirit and scope of the appended claims.

I claim:

1. In an oil burner, the combination with 70 a hollow generator formed with a series of flutes on the inner face of its top, a fuel supply pipe leading to said generator, a gas discharge pipe in communication with said generator, and a gas jet located centrally of said generator and below the same.

2. In an oil burner, the combination of a 75 hollow generator, a fuel supply pipe for said generator, a gas discharge pipe in communication with said generator, a coil located below and centrally of said generator and in communication with said gas discharge pipe, an internal casing for and supported by said coil, and a jet pipe substantially in axial alinement with said casing.

3. In an oil burner, the combination of a 80 hollow generator of discus form and provided with a series of flutes on the inner face of its top, and a jet located below and centrally of said generator.

4. In an oil burner, the combination of a 85 hollow generator, of discus form and provided with a series of flutes on the inner face of its top, a pair of fuel inlet pipes communicating with said generator at diametrically opposite points, a gas discharge pipe in communication with said generator, and a gas jet located below and centrally of said 90 generator.

5. In an oil burner, the combination of a 95 hollow generator, a shield for the bottom of said generator, a fuel supply pipe in communication with said generator, a gas discharge pipe in communication with said generator, a coil in communication with said gas discharge pipe and located below and centrally of said generator, an internal casing for said coil, and a gas jet located below and in axial alinement with said casing.

6. In an oil burner of discus form, a fuel 100 supply pipe communicating therewith, a gas discharge pipe in communication with the top of said generator and passing downwardly through said generator, and a jet carried by said discharge below said generator.

7. In an oil burner, a pair of vertical 105 fuel pipes, a generator supported by and in communication with said pipes, a shield underlying said generator, and a sleeve encircling each of said oil pipes and supporting said shield.

In witness whereof I hereunto affix my signature.

GEORGE W. WALSH.
